COMBINED TOOTHBRUSH HOLDER AND TOOTH PASTE DISPENSER

Seymour Lefco, 2837 N. Grant Blvd., Milwaukee, Wis.

Filed Aug. 1, 1963, Ser. No. 76,072

Term of patent 14 years

(Cl. D4—3)

FIG. 1 is a perspective view of one side of a combined toothbrush holder and tooth paste dispenser showing my new design;

FIG. 2 is a perspective view of the opposite side thereof;

FIG. 3 is a front elevational view thereof;

FIG. 4 is a side elevational view thereof; and

FIG. 5 is a rear elevational view thereof.

The toothbrush shown in broken lines in FIG. 1 is included for illustrative purposes only.

I claim:

The ornamental design for a combined toothbrush holder and tooth paste dispenser, as shown and described.
